UNITED STATES PATENT OFFICE.

ALGERNON EVELYN EDWARD HIORNS, OF LONDON, ENGLAND.

SAFETY RAZOR AND STROPPING APPLIANCE.

Application filed June 4, 1924, Serial No. 717,844, and in Great Britain July 20, 1923.

This invention relates to a razor stropping device, its primary object being to provide an improved stropping device of simple, durable and efficacious construction, which 5 also has the advantage that it cannot be operated if the blade to be stropped therein is not secured in the correct position, risk of damage by incorrect operation being thereby eliminated and the general convenience of 10 the device greatly enhanced. The improved stropper is particularly advantageous for use with razors in which the blade projects or may project at about a right angle to the handle and be sufficiently exposed to project 15 between a pair of rolls to sharpen the opposite sides of the cutting edge, dismembering of the razor being thus unnecessary when sharpening the blade.

With this object in view, the stropper according to the invention comprises essentially a casing in which is a slidable carrier carrying rotatable sharpening rolls which by simple manipulatory to and fro motion imparted to an operating knob as is usual, 20 are adapted to be moved into contact with the blade to be sharpened alternately on opposite sides and are also rotated so as to strop same, the blade being held stationary in the casing so as to project between the 25 stropping rolls in which position it is adapted to be locked, and means are also provided whereby the carrier is automatically locked if the blade is unlocked.

The invention also resides in the construction and combination of parts hereinafter described with reference to the accompanying drawings, and more specifically pointed out in the appended claims.

In the drawing, Fig. 1 is a plan view of 40 the preferred form of stropping device according to the invention, Fig. 2 is a sectional elevation taken on line II—II of Fig. 1 the position of the razor being indicated by dotted lines, Fig. 3 is an end sectional view 45 taken on line III—III of Fig. 2, the lid being shown closed, and Fig. 4 is a rear elevation of a portion of the device.

The apparatus comprises an outer protective casing 1 having a hinged lid 2, and longitudinally slidably within the casing 1 is a frame or carrier 3 in which are rotatably mounted pairs of stropping rolls 5, 5 and 6, 6. The pairs of rolls are arranged one at each end of the frame, and are intended for 55 fine and coarse stropping respectively. The stropping surfaces are preferably helically

formed, as shown, and the rolls in each pair are spaced somewhat apart to permit of the blade 7 to be sharpened being inserted therebetween and out of contact with either roll 60 as indicated by dotted lines in Fig. 2.

It will be understood that the stropper, though primarily intended for use with razors of the kind in which the blades can be fixed in an exposed position at about a 65 right angle to the handle, may equally well be used if the blade is mounted on a separate handle for sharpening; such is of no consequence to this invention. The razor or handle portion 8, as indicated in Fig. 2, is apertured to engage with a pin 9, one on each end wall of casing 1, and transverse supports 10 are provided to support the handle portion 8 in the correct position. When so supported, the blade 7 projects between a pair 70 of stropping rolls, so that in the medial position of the carrier 3 the rolls are spaced approximately equally on each side of said blade. The razor is adapted to be firmly secured in this position for stropping by means 75 hereinafter described.

The stropping device is driven by means of a spring cable or other flexible driving means 12 passing around one roll of each pair and secured to an operating knob 13 passing 80 through longitudinal slots in the carrier 3 and casing 1 to the outside of the latter. The rolls in each pair are geared by similar flexible bands 14, and it is evident that if the knob 13 is reciprocated relatively to carrier 3, the rolls rotate together in an opposite direction alternately with each stroke. But the device is so constructed in practice, 85 that the knob 13 frictionally engages the side of the carrier 3, the frictional force being 90 greater than that which the carrier itself offers against sliding within the casing 1 but less than that of the driving cables 12, 14 with the rolls upon which they run. The result is that upon sliding the knob 13 relative to the casing 1, the carrier 3 is first moved, one of the stropping rolls being thereby pressed against the blade; this tends to stop the carrier and the knob 13 then slides relative thereto, rotating the rolls and 95 effecting a stropping of one side of the blade. Upon reversing the movement of knob 13 the carrier immediately moves to press the co-adjacent stropping roll against the other side of the blade, the rolls then rotate, and stropping of this side is effected. The stropping action continues as long as knob 13 is recip- 100 105 110

located. It should be mentioned that for rendering the carrier 3 readily slideable in casing 1 it is mounted therein upon pins 15 which engage in slots 16 and also serve to 5 retain the carrier in position.

It is to be observed that the razor should be held very rigidly in position during stropping, or the appliances are liable to be damaged, and to prevent the latter, as also to 10 afford greater convenience and simplicity in mounting the razor in the stroppe, the appliance is so devised that the razor is locked in position upon shutting the lid of the casing, but if the lid is opened, thus releasing the razor, the carrier is automatically locked in a medial position. The razor can thus be easily removed or replaced and there is no possibility of inadvertent incorrect operation.

20 For this purpose, a blade spring 17 is mounted in casing 1, the free end of said spring engaging a fork 18 on carrier 3 and always tending to retain same in a medial position. A spring 19 is also secured within 25 in the casing 1, its upper end being formed as a detent catch 20 to engage a lip 24 on the lid 2 when closed, as shown in Fig. 3, in which position the spring 19 is pressed back clear of two inwardly projecting lugs 30 21 formed on the carrier 1. If the lid is opened however, as is effected by pressing a button 22 extending through the casing wall, the spring 19 can then lie closer to the side of the casing, whereupon it will engage between lugs 21, and so constitute a locking member for the carrier 3, and hold same rigidly in a medial position until such time as the lid is again closed. The lid 2 carries a strong leaf spring 23 which on 35 closing the lid is adapted to bear upon the razor or handle portion 8 and so hold same rigidly in place during stropping. Incidentally the device provides a convenient arrangement for safely transporting the razor 40 and stroppe.

I claim:—

1. A razor stropping appliance comprising a casing, a carrier slidably mounted for reciprocating movement within said casing, spaced stropping rolls rotatably mounted on the carrier, means for mounting a razor stationary within said casing in such position that the razor blade may project between said rolls, means for locking the razor in said position, manipulatory means for imparting reciprocating motion to the carrier to bring first one roll and then another into contact with the razor blade and which

alternately rotates the rolls in an opposite direction for each stroke, and means for locking the carrier against reciprocating movement associated with the aforesaid razor locking means so that upon unlocking the latter the carrier is automatically locked.

2. A razor stropping appliance comprising a casing, a carrier slidably mounted for reciprocating movement within said casing, spaced stropping rolls rotatably mounted on the carrier, means for mounting a razor within said casing so that the blade thereof may fixedly project between said rolls, manipulatory means for imparting reciprocating motion to the carrier to bring first one roll and then another into contact with the razor blade, and which, alternately, rotates the rolls in an opposite direction for each stroke, resilient means tending to retain the carrier in a medial position with the rolls out of contact with the razor blade, a lid for the casing adapted to lock the razor in position therein when closed, and detent means associated with the carrier and with the lid when closed for locking the carrier against reciprocation when the lid is open but not when the lid is closed.

3. A razor stropping appliance for razors wherein the blade is exposed and secured at about a right angle to the handle, comprising a casing, a razor support situated transversely of and midway between the ends of the casing, a slidable carrier within the aforesaid casing, two pairs of spaced stropping rolls journaled in and carried by the slidable carrier, endless flexible bands operatively connecting the rolls of each pair, an endless band operatively connecting the two pairs of rolls, a manipulating handle connected to said last mentioned endless band and having frictional connection with the aforesaid sliding casing, a razor retaining pin at each end of the outer protecting casing to interchangeably hold the razor with its blade projecting between the rolls of one or the other pair, resilient means tending to retain the carrier in a medial position with the rolls out of contact with the razor blade, a hinged lid on said outer casing, a combined spring-catch and carrier locking member on one wall of said outer casing, a catch on said lid to co-operate with said combined catch and locking member, and a razor retaining spring on said lid, all substantially for the purpose, and adapted to operate as hereinbefore set forth.

ALGERNON EVELYN EDWARD HIORNS.
